UNITED STATES PATENT OFFICE.

KALMON DOLGIN, OF BROOKLYN, NEW YORK, AND FRANK KOPCIENSKI, OF JERSEY CITY, NEW JERSEY.

SPRING-BED-BOTTOM FABRIC.

1,409,683.

Specification of Letters Patent. Patented Mar. 14, 1922.

Application filed March 8, 1921. Serial No. 450,656.

To all whom it may concern:

Be it known that we, KALMON DOLGIN, a citizen of the United States, and a resident of the borough of Brooklyn, county of Kings, 5 city and State of New York, and FRANK KOPCIENSKI, a citizen of Poland, and a resident of Jersey City, county of Hudson, and State of New Jersey, have invented certain new and useful Improvements in Spring- 10 Bed-Bottom Fabrics, of which the following is a specification.

The object of our invention is to attain a simple, cheap but effective structure of spring bed-bottom fabric, the parts of which 15 may be assembled with facility, and without the aid of specially skilled labor. By our construction and arrangement of parts, replacements may be easily made if necessary; and the component parts of the structure 20 separated and manipulated for cleaning, etc., and then re-assembled manually for use by persons of ordinary ability.

To this end the invention consists in the specific combination, construction and arrangement of parts and elements described 25 and claimed,—a distinctive feature being the configuration of the continuous interlocking loop hook sections as hereinafter fully set forth.

30 In the accompanying drawings,

Figure 1 is a top view of a spring bed bottom made in accordance with our invention, broken away centrally;

Fig. 2 is a side elevation of a portion 35 thereof;

Fig. 3 is a detail view of one of our continuous interlocking hook sections; and

Fig. 4 is a detail view illustrating the interlocking of the parts.

40 We use a metallic supporting frame of ordinary and well known construction, consisting of the end members e , e , angular in cross section, to which are rigidly attached the bracket socket pieces b , b , in which the 45 ends of the tubular side members a , a are mounted and supported in a manner well known in the art.

50 S are the usual spiral springs connected with the end members e , of the frame, being formed with loop hooks s , which engage with the holes e' , formed for the purpose in said end members e . Both ends of said spiral springs S are formed with loop hooks s , for coupling up not only with said end members 55 but also with the end sections of our inter-

locking loop hook sections C of which the bed bottom fabric is constituted.

Each interlocking loop hook section C is formed of a single piece of metallic wire of suitable thickness and tenacity, bent to form 60 a series of elongate loops c , connected by transverse basic ligaments c' , the basic ends of the loops c between the ligaments c' being bent into the form of duplex hooks c^2 in a plane at right angles to that of the elongated 65 loops and adapted for insertion in the bights c^x of the aforesaid elongate loops c of the next adjacent loop hook section C , as shown in the drawings, particularly in Fig. 4 thereof.

70 As will be seen from Fig. 4, the bights c^x are interlocked in the duplex hooks c^2 , by reason of the latter being given such a twist as to throw them out of the plane of the ligaments c' , the loop portions of the hooks 75 being seated in the seats thus formed, and thus the sections are held against undue movement.

The bights c^x , of one of our continuous 80 interlocking loop sections C are inserted in the loop hooks s , of the coiled springs S at one end of the frame, and the duplex hooks c^2 may also be coupled with the spring loop hooks s at the other end of the frame, as shown in Fig. 1.

85 Our interlocking loop hook sections C are made of a length equal to the width of bed bottom required, and any desired or suitable number of these sections C are coupled together to afford the requisite length of bed 90 bottom.

Our continuous one-piece interlocking loop hook sections C are of simple construction, and if made of metallic wire of suitable diameter, the unitary structure thus attained 95 insures strength and durability, while affording ease of manipulation in assembling of parts. Furthermore, the connecting means are not complex as compared with the prior state of the art, and hence more sanitary, as 100 affording less opportunity for the accumulation of dirt, and the harboring of insects, etc. In this connection the facility with which the parts may be disconnected for purposes of inspection and cleaning is of 105 practical importance, as well as the fact that the replacement of parts may be readily effected in case of necessity.

By the term bed bottom fabric we mean to designate the interlocking connected struc- 110

ture interposed between the end frame springs as herein shown and described.

What we claim as our invention and desire to secure by Letters Patent is,

5 In a bed bottom fabric of the character designated, the combination of a series of transverse interlocking loop sections each formed of a single piece of metallic wire with a plurality of elongated loops turned 10 at their free ends to form short loops in a plane at right angles to that of the elongated loops, and ligaments interconnecting the short loops, the short loops of one section being engaged by the bights of the elongated loops of the preceding section, substantially in the manner and for the purpose described.
